CLAIM

The ornamental design for a multi-compartment container, as shown and described.

DESCRIPTION

FIG. 1 is a perspective view of a multi-compartment container, embodying an alternative embodiment of the new design;

FIG. 2 is a rear elevational view thereof;

FIG. 3 is a side elevational view thereof, the opposite side elevational view being a mirror image thereof;

FIG. 4 is a front elevational view thereof; and,

FIG. 5 is a top planar view thereof.

The broken lines shown in the drawings are for illustrative purposes only and form no part of the claimed design.
